JAR

John Brady Campbell, Paramus, N.J., assignor to The Procter & Gamble Company, Cincinnati, Ohio, a corporation of Ohio

Filed Mar. 13, 1967, Ser. No. 6,177

Term of patent 14 years

(Cl. D9—86)

Fig. 2

FIG. 1 is an elevational view of a jar showing my new design.

FIG. 2 is an enlarged fragmentary view showing the profile of the base of the jar.

All elevational views of the jar are the same since the jar is circular in all cross sections.

I claim:

The ornamental design for a jar, as shown and described.
